UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPE-WRITING MACHINE.

1,252,820.

Specification of Letters Patent.

Patented Jan. 8, 1918.

Application filed July 19, 1915. Serial No. 40,572.

To all whom it may concern:

Be it known that I, ALFRED G. F. KUROWSKI, a subject of the German Empire, residing in Brooklyn borough, in the county of Kings, city and State of New York, have invented certain new and useful Improvements in Type-Writing Machines, of which the following is a specification.

The present invention relates to mechanism, especially adapted for use as part of a typewriting machine, for supporting cards in a relatively flat condition against the platen, and for effecting a line-space feed of the cards as the latter are printed or stenciled.

Card-holders of this general description are usually connected to the platen, or to the line-space mechanism of the latter, in order that in the line-spacing operation, the platen and card-holder may be moved in unison from a single key or lever, or by means of a hand wheel on the platen shaft. These connections have ordinarily been such as to prevent movement of the card-holder independently of the platen even in the operation of positioning the card for the first line to be printed thereon. For simplicity and convenience in positioning or re-positioning the card-holder, and for other reasons, as, for example, to permit the use of a record sheet, or to permit withdrawal of the card-holder from the machine without disturbing the line-space mechanism, it is desirable that, except in the line-spacing operation, the card-holder be movable independently of the platen.

To this end, an object of the present invention is a line-space mechanism for the card-holder, such that, only when operated, does it actually engage the card-holder; the card-holder being normally movable independently of the platen in either direction. A preferred form of mechanism embodying this feature of the invention comprises a card-holder which is mounted to slide in a frame rigidly attached to the carriage, the holder having fast thereto a rack adapted to be lifted by a pawl normally disengaged therefrom, and the platen shaft carrying a toothed wheel which vibrates the pawl when the shaft turns, to cause the pawl first to engage the rack and then to lift it one step on each vibration. A suitable retaining dog holds the rack after each

feed; and it may be moved to release the rack to permit free movement of the holder when desired.

A further object of this invention is a card-holder of size, shape and weight to hold heavy cards firmly, and in flat condition, while the same are fed and printed, and which to be used does not necessitate serious modification of the well-known other parts of a typewriting machine. A feature of the invention is a frame on which the holder is supported independently of the platen, and on which the holder has a sliding movement in guides of a nature to maintain the holder and the card in true alignment at all times. A further feature of the invention is a spring device for throwing the card holder to an initial or normal position, preliminary to the printing or stenciling of the first line on the card. In its preferred form, this last device consists of a pair of spring arms, detachably connected to the holder when the latter is mounted on its frame, and which exert a downward pressure on the holder to throw the latter when the retaining dog, above mentioned, is withdrawn from the line-spacing rack on the card-holder.

Other features and advantages will hereinafter appear.

In the accompanying drawings—
Figure 1 is a perspective view of the platen and platen carriage of a modified Underwood typewriting machine with the card-holder and operating mechanism of the present invention attached thereto.

Fig. 2 is a detail view in side elevation of the platen, card-holder, and pawl-and-ratchet mechanism for line-space feeding of the card-holder, the parts being shown in normal position preparatory to the printing of the first line on the card.

Fig. 3 is an elevation of the mechanism shown in Fig. 1, showing also the type bars, keys, universal bar, and other parts; the card-holder being in its normal or initial position shown in Fig. 2.

Fig. 4 is a view in side elevation of the platen, card-holder, and mechanism for supporting and feeding the latter, the full-line position of the parts being that assumed after the card-holder has been fed up by the line-space mechanism, and the position of the parts shown in broken lines being

that assumed after the card-holder has been released for its return to normal position.

Fig. 5 is a view similar to Fig. 4, except that the line-space mechanism is shown as locked to the card-holder and in the act of lifting the latter.

Fig. 6 is a top plan view of the mechanism shown in Fig. 1.

Referring to the drawings, which show the invention as applied to a modified form of an Underwood machine, the platen 7 is fast to the platen shaft 8, rotatably mounted at or near its ends in the carriage frame 9, and having the usual hand wheels 10. Also fast to the platen shaft 8 is the usual line-space ratchet wheel 11, coöperating with a pawl (not shown) on a slide 12, actuated by the line-space finger lever 13, pivoted at 14 to the carriage frame. The carriage frame 20 has its usual letter-feed movement on the rod 15 on the main frame 16. In the embodiment of the invention shown in the drawings, the platen is not shiftable between case positions, but is held in upper case 25 position by standards (not shown) on the carriage frame. A tie bar 17 is substituted for the usual rod which ties together the sides of the carriage skeleton, and the latter is secured to the carriage frame by plates 18, having ears 19 screwed at 20 to the carriage frame, and ears 21 screwed at 22 to the tie bar 17. A rod 23 ties the plates 18 together to form a rigid frame on which the card-holder is supported in a manner 30 presently to be described.

For carrying and guiding the card-holder, there is a frame having side pieces or racks 24 and 25, each of which is secured at 26 to a depending ear 27 on the tie bar 17. For further supporting the side pieces 24 and 25, there are brackets 28, secured at 29 to the carriage frame, and at 30 to the side pieces 24 and 25. The side pieces 24 and 25 are tied together at their upper ends by a rod 31, and each has a V-shaped guide 32 on which the card-holder has up and down movement.

The card-holder is comprised of side members 33 tied at their lower ends by a cross piece 34, and at their upper ends by a cross piece 35, to form a rectangular frame. Each of the members 33 has a laterally-extending flange 36, and each of the flanges 36, near its bottom and also near the top thereof, carries a roller 37, which is grooved to ride on the opposing guides 32 on the supporting frame. Each of the card-holder frame members 33 is grooved at 38 to receive one edge of the card, the bottom cross piece 34 serving as a base for the card. The card-holder supporting frame members 24 and 25 have also spring fingers 39 attached thereto, which extend over the side pieces of the card-holder and are slightly turned toward 65 the platen to press the card against the

platen at the printing line, and to compensate for possible play of the platen in its bearings.

The card-holder is normally held in its lowermost position in its supporting frame, 70 and when released is returned to such a position by means of arms 40, forked at their forward ends 42, to engage pins 43 on the side pieces 33 of the card-holder, and mounted at the rear on a sleeve 44 on the rod 23 75 which ties the plates 18. Attached at one end to the sleeve 44, and at the other end hooked under the adjacent plates 18, are coil springs 45, which tend to force down the arms 40, so that at the proper time the 80 card-holder may be thrown to normal or Fig. 1 position. Upon contact of the racks 24 and 25 with blocks 24^a and 25^a, the card-holder is arrested on reaching its lower position. It will be noted that the mere lifting of the card-holder to withdraw it from the frame, causes the pins 43 thereof to be released by the arms 40 after a sufficient upward movement of the holder. The connection of the holder to the arms 40 in placing the holder in its frame, is almost an equally simple matter. The platen being shorter than the distance between the arms 40, does not interfere with the movement of the latter.

For effecting the line-space movement of the card-holder, the following mechanism is provided: Affixed to and concentric with the platen 7 at each end thereof, is a ratchet wheel 46, the teeth 47 of which act as cams 100 to engage cam surfaces or teeth 48, one on each of a pair of arms 49. The arms 49 are affixed to a sleeve 50 adapted to rock on a shaft 51, which, for convenience, may be the paper clamp rod, and which is secured 105 at either end 52 to the carriage frame 9. The cams lift the arms 49 against the tension of springs 49^a, each attached at one end to a pin 49^b or the arm 49, and at the other end to a pin 49^c on the adjacent plate 110 18. Rotation of the platen by the line-space wheel 11 therefore causes the arms 49 to be vibrated up and down. Each of the arms 49 carries a pawl 53 pressed forward by a spring 53^a to have a normal position determined by a pin 54 on the plates 18.

On the rear face of each of the side members 33 of the card-holder is a rack 55, the teeth of which are adapted to be engaged by the pawls 53 when the latter are actuated by the cam wheels 46. The pins 54 hold the pawls normally out of engagement with the racks. When, however, the line-space wheel 11 is actuated to cause one or more of the teeth 47 on the cam wheels 46 to vibrate the arms 49, the pawls 53 are swung forward by the springs 53^a into engagement with the racks, and lift the racks and card-holder one step for each complete vibration of the arms 49. For supporting the card-holder in its 130

advanced position after each step movement of the latter, there are two dogs or pawls 56 attached to a rock shaft 57, which has bearing at either end in the brackets 28, and which carries a coil spring 59, secured at one end to the shaft and at the other end to one of the brackets 28 for normally holding the dogs 56 against the racks 55, so that on line-space movement of the card-holder, 5 the dogs are first cammed out from the racks by the inclined upper surfaces of the teeth thereof, and then by reason of the spring 59 are caused to hook under those teeth to support the card-holder in its new 10 position. If the retaining dogs 56 be disengaged from the racks when the lifting pawls 53 are also disengaged therefrom, then the card-holder is at once returned to lower position by the spring-controlled arms 15 40; and for so disengaging the dogs 56, there is provided a finger lever 60 secured to the dog-carrying shaft 57, which lever when depressed rocks the shaft 57 and thus throws the dogs 56 from the racks. The throw of 20 the dogs is determined by contact of the 25 same with the platen axle.

Referring to Fig. 3, the type keys 61 are shown mounted on key levers 62, having pin-and-slot connections at 63 with bell crank 30 interponents 64, pivoted to the frame at 65. The interponents 64 connect at 66 to the type bars 67, the latter being pivotally mounted at 68 on the type segment, so as to be thrown upward against the front of 35 the platen. Each type lever has a shoulder 69 adapted to strike the forward end of the universal bar 69^a which controls the escapement for letter feed of the carriage, and also vibrates the ribbon on each type stroke. In 40 order that the universal bar may clear the card-holder frame, it is somewhat U-shaped, as shown in Fig. 3. At its rear it is pivotally connected at 70 to a frame 71 mounted to rock on a shaft 72. It carries a bracket 45 73, which has two ears 74 and 75, and may be shifted on the universal bar to bring one or the other of the ears into pin-and-slot engagement at 76, with one arm of the ribbon-vibrating lever 77, causing a greater or 50 less throw of the ribbon according to which of the bracket ears is engaged with the vibrator, so that different color bands of the ribbon may be employed. The bracket 73 has a neutral position in which neither ear 55 engages the vibrator, and when in this position, the ribbon does not vibrate at type strokes. The bracket 73 is in neutral position when stenciling is to be effected. The 60 vibrator lever 77 is of a shape to clear the card-holder frame, and has the usual pivotal connection at 78 with the ribbon-carrier 79. Since the card-holder is inclined to the vertical, the ribbon-carrier 79 and the ribbon-shield 80 are similarly inclined, and the latter is supported by a bracket 81 held by

screws 82 to the segment bridge. The type 83 are set at an angle on the type-bars, so that the face thereof, at the printing point, may lie tangentially to the platen, and are rounded over at 85 in order that they may 70 not interfere with the type guide 84.

It will therefore be seen that the incline of the card-holder, to bring the lower part of the same beneath the platen and out of the way of the keys, has involved no serious 75 alteration of the other parts of an Underwood typewriting machine. It is also to be noted that the frame in which the card-holder is mounted to slide is carried by the carriage frame and not by the rotatable 80 parts; also that this frame provides a firm mount for the card-holder, and holds the latter in true alinement. The holder itself is a substantial structure adapted to hold and feed heavy cards, and not easily distorted. 85

Variations may be resorted to within the scope of the invention, and portions of the improvements may be used without others.

Having thus described my invention, I 90 claim:

1. The combination with a revoluble platen structure, of a card holder, means for effecting a line-space feed of the platen structure, a line-feeding mechanism for said card holder, said card holder being normally movable independently of the platen, and means to enable said platen structure to operate the line-feeding mechanism of the card-holder. 95

2. The combination with a platen, of a card holder, means for effecting a line-space feed of the platen, a separate line-feeding mechanism for said card holder, said platen and card holder being normally movable independently of each other, and means to operate said separate line-feeding mechanism. 100

3. The combination with a platen, of a card holder, means for effecting a step-by-step line-space feed of the platen, means for connecting the card holder to the platen for a step-by-step feed of the card holder with the platen, and means for automatically disconnecting the platen and card holder after each line-space feed, to permit independent movement in either direction of either the platen or the card holder. 110

4. The combination with a platen, of a card holder, means for effecting a line-space feed of the platen, means for connecting the card holder to the platen for a feed of the card holder with the platen, means for automatically disconnecting the platen and card holder after each feed, and means for holding the card holder in its advanced position after each feed. 120

5. The combination with a platen, of a card holder, means for effecting a line-space feed of the platen, means for connecting the card holder to the platen for a feed of the card holder with the platen, means 125

for automatically disconnecting the platen and card holder after each feed, and a spring-controlled dog for automatically engaging and holding the card holder after 5 each feed of the latter.

6. The combination with a platen, of a card holder, means for effecting a progressive line-space feed of the card holder past a printing line at the platen, means tending to drive the card holder in the reverse direction, and means for delivering the card holder to the action of said reverse driving means, and causing the latter to return the card holder independently of the position of 10 the platen.

7. The combination with a platen, of a card holder, means for effecting a progressive line-space feed of the card holder past a printing line at the platen, springs connected to the card holder to throw the same in the reverse direction, and means operable independently of the position of the platen for delivering the card holder at will to the action of said springs.

8. The combination with a rotatable platen, of a relatively flat card holder, a fixed frame on which the card holder is adapted to slide, means for effecting a line-space feed of the card holder on the frame, 30 and means operable while the platen is at rest to return the card holder from any position to which it has been fed.

9. The combination with a rotatable platen, of a relatively flat card holder, a fixed frame on which the card holder is adapted to slide, means for effecting a line-space feed of the card holder on the frame, and means operable independently of the 35 rotative position of the platen for throwing the card holder in the reverse direction on its frame.

10. The combination with a rotatable platen, of a relatively flat card holder, a fixed frame on which the card holder is adapted to slide, means for effecting a line-space feed of the card holder on the frame, 45 spring-controlled arms connected to the card holder for throwing the card holder in the reverse direction on its frame, means for holding the card holder against the action of said arms, and means for releasing the card holder at will to the action of said arms.

11. The combination with a rotatable platen, of means for effecting a line-space movement of the platen, a card holder, a toothed wheel rotatable with the platen, a rack on the card holder, and a dog or pawl vibratable by the teeth of said wheel to engage 55 the rack and advance the card holder step by step with the movement of said wheel.

12. The combination with a rotatable platen, of means for effecting a line-space 60 movement of the platen, a card holder, a

toothed wheel rotatable with the platen, a rack on the card holder, a dog or pawl vibratable by the teeth of said wheel to engage the rack and advance the card holder step by step with the movement of said wheel, and a spring-controlled dog to hold the card holder in its advanced position after each feed thereof.

13. The combination with a rotatable platen, of means for effecting a line-space movement of the platen, a card holder, a toothed wheel rotatable with the platen, a rack on the card holder, a dog or pawl vibratable by the teeth of said wheel to engage the rack and advance the card holder step by step with the movement of said wheel, a spring-controlled dog to hold the card holder in its advanced position after each feed thereof, and key-controlled mechanism for disengaging at will the retaining dog from the card holder to permit reverse movement of the latter.

14. The combination with a rotatable platen, of means for effecting a line-space movement of the platen, a card holder, a toothed wheel rotatable with the platen, a rack on the card holder, a pivoted arm having a cam surface for successive engagement with the teeth of said wheel as the latter is rotated, a spring for holding said arm against said wheel, and a dog or pawl carried by said arm to engage said rack and advance the card holder on each vibration of the arm.

15. The combination with a rotatable platen, and movable platen carriage, of carriage-feeding mechanism, a relatively flat card holder in front of, and extended below the platen, front-strike type-bars, and a universal bar protruding into the path of the type-bars in front of and above the base of the card holder, and extended under and upward to the rear of the card holder for engagement by the type-bars to operate the carriage-feeding mechanism on each type stroke.

16. The combination with a rotatable platen, of a relatively flat card holder, a fixed frame on which the card holder is adapted to slide, means for effecting a line-space feed of the card holder on the frame, and spring fingers attached to the frame for pressing the card against the platen at the printing line.

17. The combination with a platen, of a card holder, and means for effecting a line-space feed of the platen and card-holder, said card-holder being normally movable in either direction independently of the platen.

18. The combination with a platen, of a card-holder, means for effecting a line-space feed of the platen and card-holder, said card-holder being normally movable independently of the platen, a spring to move the card-holder in one direction, means to hold

the card-holder against such movement by said spring, and a key to release said card-holder to the action of said spring.

19. The combination with a platen, of a 5 card-holder, means for effecting a line-space feed of the platen and card-holder, said card-holder being movable independently of the platen, a spring to move the card-holder in one direction, a rack on said holder, a 10 locking dog to engage said rack and prevent the holder from being moved by said spring, and a key to release said dog and permit the holder to be moved by the spring.

20. The combination with a platen, of a 15 card-holder, means for feeding the card-holder step by step past the printing line at the platen, a spring operative to move the card-holder in the opposite direction, a reciprocatory feeding pawl or dog to engage said 20 card-holder to line-feed the same, means to hold the card-holder against movement by said spring, and a key to release the holder to the action of said spring.

21. The combination with a platen, of a 25 card-holder, means for effecting a progressive line-space feed of the card-holder past the printing line at the platen, a spring for throwing the card-holder to initial position independently of the platen, a holding device 30 to normally prevent said movement of the card-holder by the spring, and a key to release the card-holder from said holding device and permit said operation of the spring.

22. The combination with a platen, of a 35 card-holder, mechanism for line-spacing the platen and concomitantly effecting a progressive line-space feed of the card-holder past the printing line at the platen, a spring for throwing the card-holder to 40 initial position while the platen is at rest, a restraining dog to normally prevent the card-holder from being actuated by said spring, and a key to actuate said dog and thereby release the card-holder to the action 45 of said spring.

23. The combination with a rotary platen, of line-spacing mechanism to rotate the platen, a card-holder, means actuated by the line-spacing mechanism to effect a progressive line-space feed of the card-holder past 50 the printing line at the platen as the latter is line-spaced, a spring connected to the card-holder to throw the same in the reverse direction, and means operable independently of the rotative position of the platen to deliver the card-holder at will to the action of said spring.

24. In a front-strike typewriting machine, the combination with a rotary platen, line- 60 feeding mechanism therefor, and types to strike at the front face of the platen, of a card-holding frame in an upright position at the front of the platen, said frame having means for guiding and holding a card, permitting the latter to be dropped into said

frame into position at the platen to receive the type impressions, step-by-step feeding mechanism for said frame, including means to normally prevent a return movement of said frame, and a device operable to cause 70 the frame to be moved downwardly to its initial position.

25. In a front-strike typewriting machine, the combination with a rotary platen and types to strike at the front face of the platen, 75 of a card-holding frame in an upright position at the front of the platen, said frame having means for guiding and holding a card, permitting the latter to be dropped into said frame into position at the platen to receive the type impressions, line-spacing mechanism to rotate the platen step by step, and means operated by said mechanism to move the frame upwardly step by step to feed the card upwardly past the printing 85 line at the platen, said moving means comprising a separate line-spacing mechanism.

26. In a front-strike typewriting machine, the combination with a rotary platen and types to strike at the front face of the platen, 90 of a card-holding frame in an upright position at the front of the platen, said frame having means for guiding and holding a card, permitting the latter to be dropped into said frame into position at the platen, to 95 receive the type impressions, line-spacing mechanism to rotate the platen step by step, means operated by said mechanism to move the frame upwardly step by step to feed the card upwardly past the printing line at the 100 platen, a spring to move said frame downward to its starting position, a detent to hold the frame at any position to which it has been advanced by the line-spacing mechanism, and a key to actuate the detent and 105 release said frame to the action of said spring.

27. In a front-strike typewriting machine, the combination with a rotary platen, of a 110 card-holding frame provided with upright guide-ways for the edges of a card whereby the card may be dropped into said frame and held in position to receive the type impressions, a rack device on said frame, and line-spacing reciprocatory pawl mechanism to 115 engage said rack to feed said frame and card upwardly step by step at successive reciprocations of said pawl mechanism, past the printing line at the front face of the platen.

28. In a front-strike typewriting machine, the combination with a rotary platen, of a 120 card-holding frame provided with upright guide-ways for the edges of a card whereby the card may be dropped into said frame and held in position to receive the type impressions, means to feed said frame and card upwardly step by step past the printing line at the front face of the platen, and spring-holding fingers arranged to bear against the 130

outer face of the card at the printing line for holding the card firmly against the platen.

29. In a typewriting machine, the combination with a rotary platen, of guide rails extending transversely of the platen, a card-holding frame mounted to travel on said guide rails to feed a card past the printing line at the platen, and means operable independently of the platen to move the card-holding frame in the opposite direction.

30. In a typewriting machine the combination with a carriage, of a rotary platen mounted thereon, line-spacing mechanism to rotate the platen, guide rails mounted on the carriage and extending transversely of the platen, a card-holding frame mounted to travel on said rails, means operated by the line-spacing mechanism to advance said frame step by step as the platen is rotated to feed a card past the printing line at the platen, and means whereby the card-holding frame may be moved in either direction independently of the rotation of the platen, from any position to which it has been brought by the operation of the line-spacing mechanism.

31. In a typewriting machine, the combination with a carriage, of a rotary platen

mounted thereon, line-spacing mechanism for rotating the platen, upright guide rails mounted on the carriage, a card-holding frame mounted on said guide rails to travel up and down thereon, said frame having guides to receive the lateral edges of a card whereby the card may be dropped into said frame and held flat and in contact with the platen along the printing line, means actuated by the line-spacing mechanism to advance the card-holding frame step by step and thereby line space the card concomitantly with the line-spacing movement of the platen, and means to move the card-holding frame in either direction independently of the line-spacing mechanism and while the platen is at rest.

32. The combination with a platen and line-spacing mechanism therefor, of a card-holder, means for effecting a line-space feed of the platen, and a pawl-and-rack mechanism between the platen and the card-holder and operable by the platen for effecting a line-space feed of the card-holder.
